INCINERATOR

Ernest M. Minns, Temple, Tex.

Application February 21, 1955, Serial No. 489,384

6 Claims. (Cl. 110—18)

This invention relates to improvements in incinerators, and more particularly to mobile incinerators which can be readily moved from place to place, to make possible the burning of leaves, paper, garbage and the like close to the place where material has accumulated.

Various incinerators have been proposed heretofore, but these, for the most part, were not mobile, as in the case of the present device, many types were dangerous from the standpoint of spreading fire, and therefore did not meet with the approval of or receive the acceptance of sanitary commissions or fire departments.

The present device is readily movable from place to place, and is provided with an agitator which provides means for positively stirring the rubbish accumulated therein, which agitator extends below the grate, thereby enabling stirring the contents of the incinerator allowing sufficient air to intermingle with the refuse therein to produce more complete combustion.

An object of this invention is to provide a rubbish disposal unit or incinerator which is both mobile and safe, so as to make possible the burning of combustible material in congested areas.

Another object of the present invention is to provide an incinerator which may be charged with refuse, but while the refuse is burning, there is no escape of burning embers or blowing flame to endanger the surrounding area.

Still another object of this invention is to provide an incinerator which has an agitator element therein which projects below the grate thereof to make possible the thorough agitating of the material therein, thereby making possible almost complete combustion of the material within the incinerator.

A still further object of this invention is to provide an incinerator, the combustion portion is substantially enclosed for safety, yet which has sufficient draft to provide adequate combustion.

Yet another object of the invention is to provide an incinerator which is simple in construction, easy to move and safe to use.

With these objects in mind, and others that will manifest themselves as the description proceeds, reference is to be had to the accompanying drawings, in which like reference characters designate like parts in the several views thereof, in which:

Fig. 1 is a perspective view of the device embodying the invention, taken from a side and the top thereof, with parts broken away and shown in section, to illustrate the details of construction;

Fig. 2 is a vertical sectional view through the incinerator, and showing one of the agitator prongs projecting below the grate.

With more detailed reference to the drawing, the numeral 1 designates generally a cart which has a base or frame 2 on which a pair of wheels 3 are rotatably mounted, near a side of said frame. The opposite side of the supporting frame or base has a foot or leg member 4, which, with the wheels, supports the frame substan-

2

tially in horizontal position. A pair of upright standards 5 are secured to said frame, as by welding, as will best be seen from Fig. 1. These standards 5 extend upward, and have the upper ends thereof turned inward toward each other to form a handle. This handle may either be integral, inturned portions of the standards, as just described, or a separate portion joining the upper ends of the standards to form a handle may be used; the handle is designated at 6.

10 The lower and intermediate portions of the standards 5 form a cradle to support the incinerator, when in an angular position, as for moving, as will be more fully brought out hereinafter. A brace 5a extends from each standard 5 to frame 2.

An incinerator drum, generally designated by the numeral 7, is preferably made of metal and is cylindrical in shape. The drum 7 is positioned within the upstanding flanges of the angle iron frame members 2, with the drum positioned on the frame so the axis of the drum will be substantially vertical. The angle iron frame members 2 are so arranged as to seat the drum on the in-turned flanges thereof, and the up-standing flanges extend upward therearound to prevent lateral movement of the drum on the frame. A winged set screw 8 threadably engages the forward side of the up-standing flange of angle member 2 so the set screw may be tightened against the drum to securely retain the drum in place on the frame 2.

The rear portion of the cylindrical drum abuts with 30 the upright standards 5, which form a cradle when the incinerator is being wheeled from place to place. While the incinerator is used and moved on the wheeled frame, it may be readily removed therefrom, for cleaning and the like, by loosening the winged set screw 8, and simply lifting the drum upward, clear of the angle flange of the frame members 2.

The incinerator 7 has a removable grate 9 therein, which grate is supported on angle lugs 10. These angle lugs 10 are secured around the inner surface of the drum 40 at spaced intervals, as by welding, and are equidistant from the bottom 11 of the drum. Since there is no upward pressure on the grate, it merely rests on and is supported by the lugs 10, and may be readily lifted therefrom, if desired.

45 The grate 9 is preferably made of parallel bars welded to a circular support member 12, so as to be in spaced relation.

Openings 13 are formed in the cylindrical drum below the grate 9, so as to permit the interior of the drum to 50 be ventilated from below the grate, so as to produce conditions that will promote proper combustion within the incinerator. It is to be noted however, that the openings are not formed in the bottom of the drum, nor is any portion of the bottom cut away in the forming of these openings, therefore, should any burning embers fall through the grate, they will not fall from the incinerator, but will fall onto the bottom thereof, where they will not present a fire hazard.

60 A transverse shaft 14 is journaled horizontally in the cylindrical drum 7, with the axis thereof at right angles to the parallel bars of the grate 9. One end of the shaft is journaled within a collar or bearing 15, which bearing extends inward. The other end of the shaft extends through the wall of the cylindrical drum 7, and is journaled therein as indicated at 16. A C-washer or clip ring 17 interfits within a groove 16' formed within shaft 14, which prevents longitudinal outward movement of the shaft, when it is properly set in place.

65 A pair of pointed prongs or arms 14a are welded, or otherwise secured to the shaft 14, at right angles thereto and at right angles to each other. These arms are of

such length that the pointed ends will protrude below the lower surface of the parallel bars of the grate 9.

The journals 15 and 16 are preferably loose fitting, which permits the shaft 14 to be removed, as will be more fully brought out hereinafter. A crank 18 is removably secured to the outer end of the shaft 14, exterior of the drum, by means of a pin 19, which pin passes through the hub of the crank and through the shaft 14. This arrangement of the crank on the shaft, allows the contents of the drum to be thoroughly stirred, should it become packed and thus impede the circulation of air through the drum.

A cover 20 is provided for the cylindrical drum 7, which cover has handles 21 thereon to facilitate the removal thereof to permit the charging of the drum, but the cover is kept in place during the burning of the refuse, so as to eliminate the danger of burning embers escaping therefrom.

A vent pipe 22 is provided at the upper portion of the cylindrical drum 7, and is oppositely disposed from the openings 13, so as to provide proper draft through the drum. The opening from the drum into the pipe is covered with a mesh wire screen member 23, to prevent particles of burning material from passing through the flue pipe and thus present a fire hazard. The flue pipe 22 is provided with an inverted conical cover 24, which is secured thereto in spaced relation therefrom, so as to prevent entrance of rain, snow, and the like into the drum.

Operation

The incinerator drum 7 may be wheeled from place to place by slightly tilting the frame off the legs and wheeling the device to the desired place of use, which may be near an accumulation of leaves, paper, or other refuse. The lid or cover 20 is removed for charging the drum, but is replaced for the burning operation. The incinerator is placed with the openings 13 facing the wind, and the contents thereof ignited. With the openings 13 facing the wind, a draft is created through the drum and out through flue pipe 22. Normally the contents of the drum will burn vigorously, but should it become packed and thus impede the circulation of air through the drum, the crank 18 may be turned, by hand, to rotate the shaft so that the prongs 14a will be rotated through the contents of the drum, thus thoroughly stirring the contents and thus allowing the air to circulate freely therethrough. It is to be pointed out that the pointed ends of the prongs extend between and below the parallel grate bars, so that a layer of material cannot accumulate on the grate, to hinder the combustion of the material in the drum, which feature is clearly seen from the drawings.

By the removal of pin 19 and C-washer 17, the shaft 14 may be moved to the left, as viewed in Fig. 2, until the inner end passes out of collar 15, whereupon, by manipulation, the shaft may be moved inward out of engagement with bearing 16, thus the shaft may be removed from the drum, and with the shaft bearing the prongs, removed, the grate may be readily removed from the drum. It is thus readily apparent that the device is quickly disassembled for cleaning, and as readily reassembled for use.

While the device has been described and illustrated in one embodiment thereof, it is to be understood that changes may be made in the minor details of construction, and adaptations made for different uses, without departing from the spirit of the invention or the scope of the appended claims.

Having thus clearly shown and described the invention, what is claimed as new and desired to secure by Letters Patent is:

- 10 1. A mobile incinerator comprising a base, an upright cylindrical drum mounted on said base, said drum having the lower end thereof closed, and the upper end thereof open, a removable cover adapted to close the open upper end, outstanding brackets secured around the interior surface of said drum equidistant from the bottom thereof, a grate formed of parallel bars, which grate removably rests on said brackets, vent openings formed in the lower portion of the wall of said drum, said drum having a vent opening formed therein near the top thereof and oppositely disposed from the lower vent openings, a vent pipe secured in said upper vent opening of said drum, a shaft journaled in said drum intermediate said grate and the top of said drum at a right angle to said grate bars and in a plane parallel thereto, prongs secured to said shaft at right angles thereto, which prongs are of such length as to extend between and below said bars of said grate, and means on said shaft for rotating same.
- 15 2. The device substantially as set forth in claim 1, wherein; the exterior ends of said prongs are pointed.
- 20 3. The device substantially as set forth in claim 1, wherein; said prongs are pointed at their outer ends, and extend below said parallel bars of said grate and intermediate thereof, and which prongs are rotatable with said shaft.
- 25 4. The device substantially as set forth in claim 1, wherein; a crank is removably secured to the outer end of said shaft, and clip ring means on said shaft to normally retain said shaft against longitudinal, outward movement.
- 30 5. The device substantially as set forth in claim 1, wherein; said base has a transverse axle secured thereto, wheels rotatably mounted on said axle, one on each side of said base, and support means for retaining said base in horizontal position during the burning operation.
- 35 6. The device substantially as set forth in claim 1, wherein; said opening formed near the top of said drum is covered by a screen member, and said vent pipe having the exposed extremity thereof covered by a cap member which is secured thereto a spaced distance therefrom.
